A. MARSH ET AL

DATE STAMPING DEVICE

Filed Aug. 27, 1923

UNITED STATES PATENT OFFICE.

ALBERT MARSH AND HERBERT PHILIP ALAIS, OF LONDON, ENGLAND.

DATE-STAMPING DEVICE.

Application filed August 27, 1923. Serial No. 659,607.

To all whom it may concern:

Be it known that we, ALBERT MARSH and HERBERT PHILIP ALAIS, subjects of the King of Great Britain and Ireland, residing at 185 Lauderdale Mansions, Lauderdale Road, Maida Vale, London, England, and 79 Mitcham Lane, Streatham, London, England, respectively, have invented a new and useful Date-Stamping Device, of which the following is a specification.

Our invention relates to an improved date stamping device for use in conjunction with ticket delivering machines for the purpose of printing the date upon each ticket prior to its delivery by the machine, and is particularly intended for use in conjunction with the ticket delivering machine described in co-pending patent application No. 659,606 August 27th, 1923, and which may conveniently be constructed in the form of an attachment to be fitted thereto.

In carrying out this invention, we employ a date stamp comprising a series of type wheels mounted upon a spindle and adapted to be rotated thereon so as to bring different letters and figures into operative position substantially in the usual manner as employed on ordinary hand dating machines.

According to this invention, these rotatable type wheels are mounted in a hinged frame, about which they are adapted to swing. This hinged frame normally drops down until the back of the hinged frame rests against the casing in which it is mounted. It is provided with a transverse pin against which the end of a lever mounted upon the ticket delivering machine, may engage. During the operation of the machine this lever is smartly moved in an upward direction by its spring, so as to throw the frame carrying the dating wheel upwardly so that a portion thereof will strike an ink ribbon against the under surface of the ticket in the machine, so as to print the date thereon. Upon the return movement of the lever it will actuate a feeding device so as to feed the ink ribbon off one roller onto another thus ensuring a constant movement of the ribbon, and preventing undue wear in one place.

In order that our invention may be readily understood reference is made to the accompanying drawings, in which:

Fig. 1 is a perspective view showing the 55 casing of the device,

Fig. 2 is an elevation looking on the interior thereof and showing the mechanism.

Fig. 3 is a plan of Fig. 2, and

Fig. 4 is a vertical section showing the manner in which it is attached to the ticket 60 delivering machine.

Referring to the drawings, the mechanism is mounted in a casing 1 open on one face and its upper edge and closed on the other face by a plate 2. On this plate 2 are provided lugs 3 supporting a shaft 4 on which is hinged a frame 5. This frame 5 carries the mechanism of the date stamping device, and is normally held in the position shown in the drawings by means of a clamping 65 screw 6, which passes through the plate 2 and is screwed into the frame 5 as shown more particularly in Fig. 4. When it is desired to examine or adjust the mechanism, this clamping screw 6 may be released and 70 the hinged frame 5 may be turned about the shaft 4 so that it will project from the casing 1.

Loosely pivoted upon the shaft 4 are a pair of arms 7 connected at their lower ends 80 by a bar 8 and having a series of rotatable type wheels 9 supported between them in the well known manner so that they may be turned to bring any suitable combination of type into the operative position, and may 85 then be locked by the slideable locking pin 10. These arms carrying the type wheel constitute the actual printing means, and are adapted to be struck in an upward direction by means of suitable mechanism 90 provided on the machine to which the device is to be attached. On the frame 5 is provided a pair of projecting pins 11 and 12. Upon the pin 11 is mounted a spool 13 on which is wound an ink ribbon 14 which passes 95 round suitable guide rollers 15 each having wire retaining guards 16 to a take-up spool 17 mounted on the projecting pin 12. The ribbon thus passes over the type wheels 9 as indicated in Figs. 2 and 3 so that when the latter are struck in an upward direction, the ribbon will be pressed against the surface of a ticket in the machine so as to stamp the date of delivery thereon.

The spool 17 is provided with means for 105 rotating it a small amount automatically each time the device is actuated, so as to feed the ribbon off the spool 13 onto the spool 17 thus ensuring even wear and effective printing. For this purpose the 110

— spool is provided with a ratchet wheel 18 and a plate 19 pivotally mounted upon the frame at 20 is provided with a spring pawl 21 to engage in the teeth of the ratchet wheel 18 at each operation of the device. The plate 19 is slotted at 22 to permit the projecting pin 12 to pass through it and a spring 23 normally urges its free end in an upward direction. Each time the date stamping device is actuated the mechanism upon the ticket delivering machine will strike up the date stamping wheels and upon the return movement will engage the projection 24 on the plate 19 so as to press its end downwardly about the pivot 20 and against the action of the spring 23. This will engage the spring pawl 21 with the teeth of the ratchet wheel 18 so as to rotate the take-up spool 17 through a small angle, and thus feed the ribbon automatically. In order to prevent too free movement of the take-up spool 17, a suitable spring washer 25 may be provided on the projecting pin 12 and secured by a cotter pin 26 so as to exert a resilient pressure upon the side of the spool.

The date stamping device shown in the drawings is intended as an attachment for a ticket delivering machine of the type described and illustrated in our co-pending patent application No. 659,606 August 27th, 1923. It is mounted on the frame of the machine by means of apertures 27 in the frame 5 which may be slidably engaged upon projecting pins 91 provided on the frame of the machine, and indicated in dot and dash lines in Fig. 4. These pins 91 project through holes 28 in the plate 2 and a slidable locking plate 29 is mounted on this plate 2 and provided with notches 30 which engage 40 round the pins 91. The locking plate 29 is free to drop so as to engage in notches 91^a provided in the pins 91 so as to secure the attachment in position. In Fig. 4 an actuating lever 92 forming part of the machine 45 to which the device is attached is indicated in dot and dash lines. This lever is provided with a projecting pin 99 adapted to strike the arms 7 carrying the date stamping wheels 9 in an upward direction. It is also provided with a second projecting pin 100 adapted to engage and actuate the hinged plate 19 so as to operate the ribbon feeding mechanism.

We claim:—

55 1. A date stamping device for ticket delivering machines, comprising hinged arms carrying printing means, a type ribbon mounted on a spool and passing round guides and over the printing means, a take-up spool adapted to be actuated automatically at each operation of the device to feed the ribbon a small amount at each operation, a hinged frame carrying the date stamping device, a casing in which the frame is 60 hinged so that it may be turned about its hinge to give access to the mechanism, and clamping means for securing it in the casing at other times.

hinge to give access to the mechanism, and clamping means for securing it in the casing at other times.

2. A date stamping device for ticket delivering machines, comprising hinged arms carrying a series of rotatable type wheels, a type ribbon mounted on a spool and passing round guides and over the type wheels, a take-up spool adapted to be actuated automatically at each operation of the device to feed the ribbon a small amount at each operation, a hinged frame carrying the date stamping device, a casing in which the frame is hinged so that it may be turned about its hinge to give access to the mechanism, and clamping means for securing it in the casing at other times.

3. A date stamping device for ticket delivering machines, comprising hinged arms carrying printing means, a type ribbon mounted on a spool and passing round guides and over the printing means, a take-up spool, a hinged plate normally pressed in an upward direction, a pawl on the plate, a ratchet wheel on the take-up spool with which the pawl engages to rotate the spool through a small angle at each operation of the device, a hinged frame carrying the date stamping device, a casing in which the frame is hinged so that it may be turned about its hinge to give access to the mechanism, and clamping means for securing it in the casing at other times.

4. A date stamping device for ticket delivering machines, comprising hinged arms carrying a series of rotatable type wheels, a type ribbon mounted on a spool and passing round guides and over the type wheels, a take-up spool, a hinged plate normally pressed in an upward direction, a pawl on the plate, a ratchet wheel on the take-up spool with which the pawl engages to rotate the spool through a small angle at each operation of the device, a hinged frame carrying the date stamping device, a casing in which the frame is hinged so that it may be turned about its hinge to give access to the mechanism, and clamping means for securing it in the casing at other times.

5. A date stamping device for ticket delivering machines, comprising hinged arms carrying printing means, a type ribbon mounted on a spool and passing round guides and over the printing means, a take-up spool adapted to be actuated automatically at each operation of the device to feed the ribbon a small amount at each operation, a hinged frame carrying the date stamping device, a casing in which the frame is hinged so that it may be turned about its hinge to give access to the mechanism, clamping means for securing it in the casing at other times, perforated bosses in the frame to engage over fixed pins on the frame of the machine on which the de-

vice is used and a slidable plate adapted to engage partly over apertures in the casing through which these pins project so as to enter notches in the pins to retain the device in position.

6. A date stamping device for ticket delivering machines, comprising hinged arms carrying a series of rotatable type wheels, a type ribbon mounted on a spool and passing round guides and over the type wheels, a take-up spool adapted to be actuated automatically at each operation of the device to feed the ribbon a small amount at each operation, a hinged frame carrying the date stamping device, a casing in which the frame is hinged so that it may be turned about its hinge to give access to the mechanism, clamping means for securing it in the casing at other times, perforated bosses in the frame to engage over fixed pins on the frame of the machine on which the device is used and a slidable plate adapted to engage partly over apertures in the casing

through which these pins project so as to enter notches in the pins to retain the device in position.

7. A date stamping device for ticket delivering machines, comprising hinged arms carrying printing means, a type ribbon mounted on a spool and passing round guides and over the printing means, a take-up spool, a hinged plate normally pressed in an upward direction, a pawl on the plate, a ratchet wheel on the take up spool with which the pawl engages to rotate the spool through a small angle at each operation of the device, perforated bosses in the frame to engage over fixed pins on the frame of the machine on which the device is used and a slidable plate adapted to engage partly over apertures in the casing through which these pins project so as to enter notches in the pins to retain the device in position.

ALBERT MARSH.
HERBERT PHILIP ALAIS.
